(57) **CLAIM**

The ornamental design for a display screen with graphical user interface, as shown and described.

DESCRIPTION

FIG. 1 is a front view of a display screen with graphical user interface according to our new design, the view showing a first image in a sequence of movement of the graphical user interface;

FIG. 2 is another view thereof showing a second image in the sequence of movement of the graphical user interface; FIG. 3 is another view thereof showing a third image in the sequence of movement of the graphical user interface; FIG. 4 is another view thereof showing a fourth image in the sequence of movement of the graphical user interface; FIG. 5 is another view thereof showing a fifth image in the sequence of movement of the graphical user interface; FIG. 6 is another view thereof showing a sixth image in the sequence of movement of the graphical user interface; FIG. 7 is another view thereof showing a seventh image in the sequence of movement of the graphical user interface; FIG. 8 is a front view of a display screen with graphical user interface according to another embodiment of our new design, the view showing a first image in a sequence of movement of the graphical user interface;

FIG. 9 is another view thereof showing a second image in the sequence of movement of the graphical user interface; FIG. 10 is another view thereof showing a third image in the sequence of movement of the graphical user interface;

(Continued)

FIG. 11 is another view thereof showing a fourth image in the sequence of movement of the graphical user interface; FIG. 12 is another view thereof showing a fifth image in the sequence of movement of the graphical user interface; FIG. 13 is another view thereof showing a sixth image in the sequence of movement of the graphical user interface; and, FIG. 14 is another view thereof showing a seventh image in the sequence of movement of the graphical user interface. The dot-dash line representations of the display screen in the figures form no part of the claimed design. The dashed line representations of interface environment in the figures form no part of the claimed design.

The outermost broken lines illustrate a display screen and form no part of the claimed design. The stippling illustrates a contrasting appearance. The remaining broken lines illustrate portions of the graphical user interface that form no part of the claimed design.

The appearance of the embodiments of the graphical user interface sequentially transitions between the sets of images shown in FIGS. 1-7 and 8-14, respectively. The process or period in which one image transitions to another forms no part of the claimed design.
